UNITED STATES PATENT OFFICE

2,241,102

CALCULATING MACHINE

Joseph A. V. Turck, Wilmette Ill., assignor to Felt
& Tarrant Manufacturing Company, Chicago,
Ill., a corporation of Illinois

Application May 16, 1930, Serial No. 452,876
Renewed March 29, 1939

10 Claims. (Cl. 235—62)

This invention relates in general to improvements in calculating machines and, while it has more particular reference to improvements in calculating machines wherein additive actuating mechanisms are optionally arrangeable for key responsive operation and/or key set operation (an example of which is disclosed in United States Letters Patent No. 1,926,826, issued September 12, 1933) it will be apparent that certain features of the invention have other and more general valuable application.

The principal object of the present invention is the provision of a motor driven calculating machine of improved construction wherein the banks of ordinally arranged digital keys may be optionally operated as a key responsive calculating machine for addition and subtraction and as a key set machine for multiplication and division and in association therewith to provide a shiftable carriage in which the numeral wheels and accumulator mechanism will be mounted and which may be progressively arranged in co-operative relation with the set-up multiplicand for ordinal reception of the adding movements in accordance with a multiplier.

Another important object of the invention is the provision of a motor-driven calculating machine of the key responsive type wherein, after a multiple computation has been accomplished, the multiplicand, the multiplier, and the product will all be displayed to the operator, or if of a negative form, the dividend, remainder, a check on the dividend and divisor are so displayed.

Another important object of the invention is the provision of a calculating machine to provide an automatic control mechanism of improved construction and arrangement for automatically controlling the series of actuations delivered to the carriage accumulator mechanism in multiple calculation with the positive, as in multiplication, or negative, as in division.

Another important object of the invention is the provision of an error control mechanism operative with both the key responsive and key set mechanisms and acting to lock the automatic digital control devices in the event that error is made in setting up the multiplicand or divisor on the keyboard.

Another important object of the invention is the provision of a locking mechanism for preventing manipulation of the multiplier keys when the ordinal actuating mechanisms are arranged for key responsive action.

Another important object of the invention is the provision of locking mechanism and devices

for preventing manipulation of any of the keys of the keyboard when the shiftable carriage is out of cooperative registration with the ordinal additive actuating mechanism.

5 Numerous other objects and advantages of the invention will be apparent as it is better understood from the following description which, taken in connection with the accompanying drawings, discloses a preferred embodiment thereof.

10 Referring to the drawings,

Figure 1 is a plan view of a calculating machine embodying my present invention;

Fig. 2 is a side elevation thereof taken from the right;

15 Fig. 3 is a side elevation taken from the left, parts being broken away and shown in section;

Fig. 4 is a rear elevation of the same with a portion of the casing broken away;

20 Fig. 5 is a front to back vertical section taken at the right of the righthand digital order of the machine;

Fig. 6 is an enlarged detail portion of the mechanism disclosed in Fig. 5, and showing the position the parts assume in an adding movement;

25 Figs. 7 and 8 are enlarged fragmentary details of the means for releasing the hook from the power member;

Fig. 9 is an elevation of a portion of the error control mechanism;

30 Fig. 10 is an enlarged fragmentary detail of a portion of the error control mechanism;

Fig. 11 is a section taken substantially on the line 11—11 of Fig. 10;

35 Fig. 12 is a section taken across certain parts of the error control mechanism;

Fig. 13 is a front to back vertical sectional view taken through the machine and alongside the multiple control mechanism;

40 Fig. 14 is an enlarged fragmentary detail of the same;

Fig. 15 is a view similar to Fig. 13 and showing the parts in different relation;

Fig. 15—a is an enlarged detail of certain 45 latching detents;

Fig. 16 is an enlarged fragmentary view showing the multiple control segment and its engaging devices;

Fig. 17 is a vertical front to back sectional view illustrating means by which power is transmitted from the motor drive to the multiple control mechanism and likewise the universal keyboard clearing device provided for use in key set operation;

55 Fig. 18 is a partial transverse sectional view,

greatly enlarged, through a portion of the machine and showing details of construction; and

Fig. 19 is a vertical front to back section taken adjacent the lefthand side of the machine and showing a mechanism for arranging the parts 5 optionally for key responsive and key set operation.

The calculating machine shown on the drawings, and constituting the embodiment of the invention at present preferred, comprises a casing formed of a base plate 51, a top plate 52, a front wall 53, a rear wall 54, a righthand side wall 55 and a lefthand side wall 56. The bottom and vertical walls may, if desired, be provided with sound deadening and cushioning packing 57. The operative parts are mounted in and carried by a framework which consists of right and lefthand supporting side plates 58 and 59 and intermediate partition plates 61, all extending from front to back of the machine and held in rigid relation by tie rods 62 upon which are mounted spacing bushings or sleeves 63. The machine shown on the drawings is of ordinal character and a plurality of accumulator actuating mechanisms for accumulator actuating units is provided, and the several actuating mechanisms of the adding orders of the machine are arranged between the partition plates 61 as in Patent No. 1,926,826 hereinbefore referred to. Each adding order of the machine is provided with a series of digital control keys 64, each such series comprising nine keys bearing the numbers 1 to 9 to be used in addition and multiplication and their complements to be used in subtraction and division.

A plurality of accumulator units, generally indicated by reference characters 65, are mounted in a shiftable carriage generally indicated by reference character 66, which, as will presently be more fully explained, is shiftable transversely of the actuating units and into progressive co-operative relation therewith to cause predetermined additive actuations to be received by and stored in predetermined desired accumulator units. The carriage comprises generally a frame consisting of partition plates 67 secured in spaced relation by tie rods 68 and bushings 69. The carriage is pivoted upon a cross-rod 71 mounted in upward extensions 72 of the side supporting plates 58 and 59 and rests upon a trackway 73 in turn supported upon and fixed to said supporting plates. The carriage is provided with a carriage housing 74 enclosing its rear, top, front and ends, leaving the bottom open for co-operative engagement between the accumulator units and the additive actuating mechanisms.

Each accumulator unit is or may be that described in my aforementioned patent and comprises a numeral wheel 75 adapted to be viewed through sight openings 76 in the casing housing 74 and carrying a pinion 77 in mesh with a pinion 78 which in turn co-operates through a cyclic gear 80 with a gear 79 which forms a transmitting gear mechanism for advancing the numeral wheels by the desired adding movements and in accordance with the degree of actuation of the ordinal column actuators as received by a ratchet gear mechanism 81 fixed upon a cross-rod or shaft 82 carried in the main frame of the machine.

In the movement of the carriage and its contained accumulator units across the machine, the gears 79 are disengaged from the ratchet gear mechanism 81 at the beginning of a shifting movement and reentrained in co-operative relation with other ratchet gear mechanisms as may

be desired in the calculation. The carrying is accomplished by power stored in carrying springs 83 through parts and devices identically like those shown in my patent already mentioned and particular showing or description of them is, therefore, thought unnecessary to an understanding of the present invention. The adding movements are, of course, determined in amount by the particular keys depressed.

10 Each key 64 is provided with a downwardly extending stem 84 arranged through the keyboard plate 52 and through sub-plates 85 and 86. Springs 87 are provided to hold the keys in elevated position and to return them after each key stroke. Each order of the machine includes a digital control stop bar 88 arranged to extend beneath the lower end of the key stems when the keys are in elevated position and to be pulled rearwardly of the machine in amount determined by the additive value of the particular key of the order depressed. The stop bar 88 is provided with differentially spaced lugs 89 adapted to engage the depressed key stem of the order, the spacing being such that the stop bar 88 has an increasing 15 unit movement from the 1-key at the front to the 9-key at the rear of the associated order of the keys.

20 A link 91 is connected at 92 with a downwardly extending arm or lug 93 on the stop bar 88 and at 94 to a link 95 in turn connected at 96 to a rock sector 97 pivoted upon a cross-rod 98 and provided with teeth continuously in engagement with a pinion 99 forming a part of the ratchet gear mechanism 81. The link 95 is pivotally connected at its other or front end 101 with an arm 102 of a friction device 103 carried upon a shaft or rod 104 extending across the machine and having bearing in the partition plates 61. A spring 105 is connected at 106 with a link 121 to 25 be later described and at 107 to the frame of the machine. Upon an adding movement, depression of the sector is accomplished by continuously moving power mechanism to which it is connected by depression of a key, the result of this connection to the power being that the associated rack sector 97 is swung down the desired amount with a consequent extension of the spring 105 and the storing in it of power to accomplish the adding movement upon disconnection of the actuating 30 unit affected from the power means.

35 This power means comprises an electric motor 108 (Figs. 3 and 4). The motor 108 is secured to and carried by supporting plates 109 fixed in the frame at the rear of the machine, current being supplied to the motor through suitable electric wiring and controls indicated generally at 111. It is not believed that a detailed description of the motor 108 and the wiring for its supply of current is necessary to an understanding of the 40 instant invention. The motor rotates continuously when the machine is in use.

45 The motor shaft 112 carries a pinion 113 in mesh with an idler gear 114 which carries a pinion 115 in mesh with a gear 116 upon a shaft 117 extending across the several columns or orders 50 of the adding machine. This shaft 117 is provided with a toothed wheel 118 for each order of the adding machine, these toothed wheels 118 being arranged adjacent the several actuating units or mechanisms.

55 Referring to Figs. 5 and 6, it will be noted that the friction device 103 of each actuating mechanism is provided with an arm 119 pivotally connected at 120 with a link 121 in turn pivoted at 122 in an upright guard arm 123 pivotally

mounted upon a cross-pin or rod 124 extending across the frame. An arm 125 having a tooth or hook 126 at its free end and a spring lifted lever 127 are also pivoted to the upper end of the guard arm 123 on pivot 122. The spring lever 127 is arranged within or beneath a bent-over portion 128 of the hook arm 125 and has a lip 129 extending over toward the hook arm 125 at the rear end of the spring lever 127. A spring 131 is wound about the pivot 122 and normally holds the hook arm 125 in engagement with the spring arm 127. A spring 132 is secured at 133 to the lower portion of the guard arm 123 and to the front end of the spring lever 127 at 130 and tends to lift the free end of spring lever 127 upwardly to sustain the hook 126 of arm 125 normally out of contact with the toothed wheel 118.

In accomplishing a calculating operation, depression of a key causes the hook arm 125 to engage the toothed wheel 118 and to be moved a full stroke of the machine. The hook arm 125 is provided with two downwardly extending lugs or projections 136 and 137 adapted to be engaged by teeth of the wheel 118 forwardly of the tooth engaged by the hook as the hook is drawn rearwardly, to lift or cam the hook upwardly and positively disconnect the hook from the engaged tooth at the end of a predetermined adding movement, as may be readily observed from Figs. 7 and 8, whereupon the spring 132 returns the hook arm 125 to its normal level. The power strokes thus induced are all of a predetermined travel which is the same for all digital values. A sector or rack segment 97 is moved downwardly in this power stroke, only the amount permitted by the particular digital key depressed, downward movement of the sector continuing until halted by engagement of the stop bar 88 with the key stem of the key depressed. The friction device 103 permits continuation of the movement of the link 121 after the halting of its associated sector 97. The power stroke extends the spring 105 and stores up in it the power needed to accomplish the adding actuation of the accumulator. Upon disconnection of the hook 126 from the toothed wheel, the spring 105 moves the parts back to normal position, the latter part of this movement being accompanied by an upward movement of the rack sector 97, and, through toothed wheel mechanism 81, by the desired advancement of the numeral wheel of the associated accumulator unit. The earlier part of the return movement under the impulse of spring 105 is taken up in the friction device 103.

The control of the hook 125 prevents its engagement with the toothed wheel 118 until a particular key depressed is locked down into depressed position where it must remain until released. A parallel motion device is provided for each actuating unit and includes an equalizing key bar 138 pivoted at 139 and 141 respectively to levers 142 and 143, which in turn are pivoted at 144 on rods extending through the partition plates of the frame. The parallel motion device also includes a bottom bar or link 145 pivoted at 146 to the lower ends of the levers 142 and 143. A key locking bar 147 (Figs. 5 and 18) is pivoted at each end at 148 to the upper ends of the levers 142 and 143 and is provided with locking fingers 149 adapted to enter into conically faced openings 151 (Fig. 18) of the key stems as they are depressed. A key stem in being moved down upon depression of the key engages the upper surface of the key bar 138. Depression of this bar by a key stem in its parallel motion swings the levers

142 and 143 in a clockwise direction and causes the adjacently arranged locking finger 149 to enter into the presented opening 151 of the stem 84 of the key depressed.

The springs 131 and 132 normally hold the hook arm 125 in an elevated position and clear of its toothed wheel. The hook arm 125 is normally arranged in elevated position and has a laterally extending shoulder or lip 152 which is normally disposed a short distance above an appropriately arranged lip 153 provided on the rear end of the link 145, and is adapted to engage the upper side of lip 153 upon depression of hook arm 125. The key bar 138 carries a downwardly extending dog 154 which is provided at its lower end with a lug 155 arranged above and in position to engage the lug 129 upon the spring lever 127, this dog being normally held in a rearward position by a spring 157 tending to swing the dog in a counterclockwise direction (viewing Fig. 6) and maintaining a shoulder 158 extending up from the dog and in engagement with a shoulder 159 on the bar 138.

Upon depression of a key, the dog 154 depresses the spring lever or arm 127, the hook arm 125 being held up at this instant by the interengagement of its lug 152 on top of the lug 153 at the rear end of link 145. The depression of the key moves down its equalizing bar 138 and moves also the link 145 toward the front of the machine, this motion being accomplished through the swinging of the levers 142 and 143.

The downward movement of the spring lifted arm 127 provides the proper tensioning of spring 131 so that when the hook arm 125 drops, the hook will make full engagement with the presented tooth of wheel 118, and as soon as the lip 153 on the link or bar 145 moves from under the lip 152 on the hook arm, the hook drops down into engagement with the toothed wheel 118, the drop being accelerated by tensioning spring 131. Having engaged the ratchet power wheel, which it will be remembered is continuously rotated, the hook is carried rearwardly until the cam lugs or projections 136 and 137 engage succeeding teeth and positively disconnect the hook from the toothed wheel at the end of the desired stroke which, through the parts described, moves the rack sector 97 down into position to produce the desired adding movements in the accumulator on the return stroke. A spring 161 is connected to the key bar and to the lever 142 and normally tends to move the parts of the parallel motion device to raise the key bar when a key is released after depression.

The machine shown on the drawings contemplates the locking down of a depressed key and also of the key bar 138 until the rearward movement of the link 121 is nearly completed. A bent lug 162 is provided upon the lower bar 145 of the parallel motion device and a hook latch 163 is pivoted at 164 on the key bar 138 in position to hook over the bent lug 162 before the key bar reaches its lowest position under the key stroke. In order that this locking down of the key bar and of the key may be accurately released after predetermined travel of the parts, a pin 165 is provided upon the link 121 in position to engage a downwardly extending finger 166 formed integral with the hook latch 163, striking of the pin 165 against this finger 166 unhooking the latch and permitting the parts to rise again to normal position.

Mechanism is provided to prevent reengagement of the latch 163 with the lug 162 if the key

be held for more time than is required for the calculating operation. The dog 154 is provided with a forwardly extending finger 167 normally arranged beneath a lug 168 on the end of the hook latch 163. After the hook 126 becomes disengaged from the power toothed wheel, the spring 105 moves the link 121, the spring arm 127 and the hook arm back toward the front of the machine. In this movement, if a key be held depressed, the lug 129, already mentioned, on the spring arm, strikes against the lug 155 swinging the dog 154 toward the front of the machine and causing the finger 167 to raise the hook latch 163 out of engagement with the lug 162 and the finger 167 acts to hold the hook latch out of operative position until the key is released. Continued depression of the key prevents reengagement of the lug 155 of the dog 154 upon the top of lug 129. Upon release the parts are then moved back into position by the spring 161.

As has been earlier stated, the machine shown on the drawings and disclosing the preferred embodiment of the invention is adapted for operation either as a power-driven key responsive calculating machine or as a power-driven key set machine for automatic actuation.

Referring now to Figs. 1 and 19, it will be noted that at the left of the series of ordinal banks or rows of adding keys are two keys indicated respectively by reference characters 181 and 182, the former being labeled "key act" and the latter "auto act." These keys are adapted for alternate depression, the depression of one key raising the other. When it is desired to use the adding machine for key responsive operation, the key 181 is or must be arranged in depressed position and when it is desired to use the calculating machine for key set automatic repeated actuations, as in multiplication and negatively as in division, the key 182 is or must be depressed. These two keys have key stems 183 extending down through the keyboard plate 52 and the sub-plates 85 and 86 and springs 184 are provided to lift the keys when occasion permits.

A walking beam lever 185 is pivoted upon a cross-rod 186 just below the keys and this lever has an end 187 located beneath each key. It has also at each end a lock arm or finger 188 adapted to enter into an aperture in the key stem when the key is depressed and the engaged end of the lever swung downwardly to lock the parts in the assumed position. The walking beam also has a downwardly extending arm 189 provided with a V-shaped lug or bottom 191 which may engage in either of two slots 192 in a spring lock lever 193 pivoted upon a cross-rod 194 carried by the frame. A spring 195 normally tends to lift the lever 193 and maintain engagement with the V-bottom of the walking beam lever 185. The arm 189 of this lever is connected at 196 with a link 197 extending toward the back of the machine and this link is in turn connected at 198 with an arm 199 fixed upon a cross-shaft 201 having suitable bearings in the frame and extending past the various orders of actuating mechanisms. This shaft is arranged closely adjacent the dogs 154 (Fig. 6), which it will be remembered serve to depress the spring levers 127 and through them the hook members 125 into engagement with the power toothed wheel. The shaft 201 is milled to its center at 202 adjacent each dog 154. An arm or finger 204 is provided on the dog to extend into the milled portion of the shaft when the parts are arranged for key responsive action. When, however, the key 182 is pressed, the shaft 75

201 is rocked in a counterclockwise direction (viewing Fig. 5) and all of the dogs of the several orders are swung toward the front of the machine moving their lugs or projections 155 out of registration with the lugs or lips 129 of the spring levers 127. This movement of the dogs also lifts the hook latches 163. Depression of the keys with the parts thus arranged does not cause engagement of any of the hooks with their companion toothed power wheels. When the machine is thus arranged, advancement of the accumulator mechanism in desired amounts is otherwise accomplished as will be presently explained.

Means are provided for holding the keys and the parallel motion mechanism in the positions they assume upon key depression. Referring now to the lefthand end of Fig. 5, it will be noted that the forward ends of the links 145 are formed into lugs 205 arranged adjacent companion lugs 206 on latch arms 207 pivoted upon a cross-rod 208 in the frame. Each latch 207 is provided with an arm 209 having its end arranged adjacent a shaft 211 also extending across the machine and through suitable bearings. This shaft is milled to its center at 212 adjacent each latch arm 209 and when swung in a clockwise direction (viewing Fig. 5) a spring 213 fast to the latch arms and to a rod 214 extending across the frame will pull the latch arms up into position to be engaged with the latch extension or lug 205 of the link 145 when a key is depressed to move the parallel motion device of its order. When the latch arms are rendered operative the lugs 206 of the latch arms raise into contact with the latch extension 205 of its companion parallel motion device and upon rearward movement of the link 145 becomes locked in hooked engagement with the latch arm.

Referring now to Fig. 19, it will be noted that the shaft 211 carries a fixed arm 215 arranged in front to back general registration with walking beam lever 185. The arm 215 is pivotally connected at 216 with a link 217 which extends to the arm 189 of the walking beam lever and is slotted at 218 to receive a pin 219 fixed to the arm 189. A spring 221 normally holds the pin 219 in the forward end of the slot 218.

It will be noted that the forward movement of the dogs 154 out of operative position with the spring levers 127 results in no depression of these levers when a key is pushed down and the mechanism locked in the key set position just described. The spring lever 127 and the hook arm 125 of the order involved are held up by the companion spring 132 until actuated by supplemental mechanism, which will be presently described, this mechanism being adapted to produce repeated actuations to accomplish multiplication and without the release or resetting of the particular key of the actuating mechanism depressed.

A shaft 222, having bearing in the frame, is arranged to extend across the several orders of additive actuating mechanisms and is provided with an arm 223 fixed to it and arranged adjacent each such order. A latch 224 is pivoted on each arm 223 at 225 and extends up to above a pin 226 fixed on the companion spring lever 127. Each latch 224 is provided with a hook 227 at its upper end, adapted to engage over the pin 226 and depress the spring lever 127 each time the shaft 222 is rocked in a clockwise direction (viewing Fig. 6). A stud 228 is arranged to extend out to the left from the adjacent partition plate

of the frame and forms a stop limiting rearward movement of the latch 224. A spring 229 is provided at the pivot 225 to urge the latch 224 toward this stop stud.

It is intended, as will be more fully explained, that the shaft 222 will be oscillated the number of times determined by the digital value of the multiplier, and that like repeated depressions of the spring lifted levers 127 will be accomplished. Additive accumulation will be produced in the 10 accumulator in accordance with the digital values of the keys depressed and locked in key set position. Each engagement of the hooks of the orders with their toothed power wheels will carry the pins 226 out of engagement with the latches 224. However, upon completion of the operative power stroke, the parts return to the position shown in Fig. 5 with the latches 224 again in position to depress the spring levers 127.

Referring now to Figs. 1, 13 and 14, it will be noted that a column or bank of keys 231 is arranged at the right hand side of the keyboard and one space removed from the ordinal columns of keys 64. These keys 231 are constructed and arranged like the keys 64 and like them also are provided with stems 232 adapted to actuate a parallel motion device comprised of an equalizing key bar 234, two levers 235 and 236, pivoted respectively upon cross-rods 144, and a lower bar 239 pivoted at its ends to the levers 235 and 236. A key locking bar 241 is pivoted in the levers 235 and 236 and has locking fingers 242 adapted to enter into openings in the keys exactly as do locking fingers 149 of the lock bars 147 in the key stems 84. The keys 231 are multiplier keys and depression of any one of them results in the connection of the hook arm 125 with the toothed power wheel for the number of repeated additive operations indicated by the key depressed, i. e. one addition of the set-up multiplicand if the front key, namely the 1-key, be depressed; two additions if the second key from the front key be depressed, etc.

A ratchet segment 243 is pivotally mounted to rotate about the cross-rod or shaft 98 upon which are mounted the rack sectors 97, already described, and this ratchet segment 243 is disposed in position to control the number of reciprocations imparted to the latch 224 in number corresponding to the digital value of the particular key 231 depressed by the operator. In the instant embodiment of the invention the rack sectors 97 extend up to and to the rear from the pivotal supporting rod 98, and the ratchet segment 243 extends downwardly from the rod 98 and into co-operative relation with certain parts and devices to be presently described.

An arm 244 extends up above the ratchet segment 243 and is pivotally connected at 245 with a link 246 in turn connected at 247 with a differentially movable slide bar 248 constructed, mounted and controlled like the bars 88 of the additive actuating units earlier described. Depression of a key 231 results in a movement of the ratchet segment 243 in an idle clockwise stroke (viewing Fig. 13) in amount determined by the value of the particular key depressed. A spring 249 is connected at one end at 251 to the right hand partition plate of the frame and at 252 to the upwardly extending arm 244 forming a part of the ratchet segment member. This spring at all times tends to move the ratchet segment in a clockwise direction (viewing Fig. 13) and upon depression of the key the ratchet segment moves down and toward the front of the machine until halted by engagement of the 75

adjacent differentially arranged projection 253 upon the slide bar 248 with the stem of the key depressed. Means are provided, which will be presently described, for returning the ratchet segment toward its normal position a one-tooth spacing for each operation of the latch hooks 224, i. e. for each adding accumulation of the multiplicand set up on the main keyboard of the machine.

The spring 249 is under tension, as has been explained, and is restrained in its pulling movement upon the ratchet segment 243 and the bar 248 by a latch 254 pivoted at 255 on the bar 248 and having a hooked forward end 256 normally engaging over a stop lug 257 upon a cleat or member 258 fixed to the adjacent partition plate of the frame at 260. The construction and arrangement of the parts is such that upon depression of a key 231 the latch 254 will be disengaged from its holding lug 257 and the differential stop bar 248 may then be pulled rearwardly of the machine by the spring 249 and the ratchet segment 243 moved as already described and until the appropriate differential projection 253 of the bar 248 engages the lowered key stem.

25 A latch dog 259 is pivoted at 261 on the equalizer key bar 234 and has its latched end normally arranged above a tail or lug 262 on the rear end of the latch 254. When the equalizer key bar 234 is moved downwardly by the depression of a key, the dog 259 rocks the latch 254, as will be readily understood, and releases the differential bar. A spring 263, fixed to the dog 259 below its pivot, and at 264 to the key bar 234, presses the dog into active engagement with the latch 254 to maintain the parts normally in the locked relation just described.

As has been hereinbefore partially explained, the ratchet segment 243 is provided with teeth, 40 each of which represents the unit difference between the progressively valued keys 231 and, as additive actuations are imparted by the latches 224 through the spring levers 127, the ratchet segment 243 is returned tooth by tooth to its normal zero value position.

When the ratchet segment is set by the depression of one of the keys 231 for a predetermined automatically controlled repetition of additive movements, means are provided to hold the equalizer key bar 234 and the depressed key in set position until the instigated calculation is completed, which means will be presently described.

Upon depression of any one of the keys 231 a 55 reciprocatory movement is automatically imparted to the shaft 222. At the righthand side and beneath the bank of keys 231 an arm 273 is fixed upon this shaft and has pivotal connection at 274 with a link 275 pivotally connected at 276 in a guard arm 277 extending up from a lower pivotal mounting 278 in the frame of the machine. A spring 279, fixed at the front at 281 in the frame of the machine, is connected to the forward end of the link 275 at 282 and tends to pull the arm 273, which is fixed on the shaft 222, toward the front of the machine. Periodic controlled reciprocation rearwardly of the machine is imparted to the arm 273 and shaft 222 under the control of the keys 231.

Referring now to Fig. 17, it will be noted that a gear 283 is fixed upon power shaft 117 and in the column space between the keyboard of the keys 231 and the keyboard of keys 64. The gear 283, of course, rotates continuously and is in mesh with a pinion 284 pivoted upon a stud

shaft 285 and carrying a crank or eccentric pin 286. A link or connecting rod 287 engages the crank pin 286 and a pin 288 provided at the upper end of an oscillating arm 289, which is pivoted upon a rod 291 arranged for bearing support in or near the bottom of frame of the machine.

The lever 289 is provided at its top with a cross plate 292, which extends over into the space occupied by the mechanisms controlled from the keys 231 and in its continued oscillatory reciprocation is arranged to actuate such mechanisms to impart the plural or multiple actuation of the additive actuating mechanism already described.

The plate 292 is adapted to be engaged, as calculating operations of the machine may require, by the hook end 293 of a hook member 294 pivoted at 295 in the upper end of a guide arm 277 in turn pivoted at 278 at or near the base of the frame and already described. A spring lever 298, much like the spring lever 127, is provided to control the action of the hook member 294 and is pivotally supported with this member at 295. A spring 299, arranged about the pivot 295, acts to hold the spring lever 298 and the hook member 294 in closely adjacent coincident relation.

A spring 301 is arranged between the base of the guide arm 277 at 302 and the rear end of the spring lever 298 to lift the spring lever as occasion may permit.

The engagement of the hook 293 with the plate 292, as the plate 292 reciprocates, is accomplished as the result of the depression of the key 231. A forwardly extending horizontal arm 304 is pivoted at 305 in a downward projection of the equalizer key bar 234 and this arm is arranged for engagement with a roller 306 mounted at 307 on the spring lever 298. The arm 304 at its forward end is provided with a bent lip or lug 309 arranged beneath the lower bar 239 of the parallel motion device controlled by the keys 231. This lug limits upward movement of the arm 304 and the arm is provided with an upwardly arranged hook 310 adapted to engage over the pivot 261 of the latch dog 259. Upon depression of a key, the latch dog 259 releases the hook lever 254, and has its lower end resting upon the ledge 309. Depression of a key, therefore, moves the spring lever down since the roller 306 is pressed down by the arm 304. The hook 293, however, is held up by interengagement of lugs 311 and 312, as will be presently described, to allow the necessary time for the ratchet segment 243 to be swung to its position as determined by the particular digital key 231 which has been depressed.

Referring now to Fig. 15—*a*, the hook member 294 is provided near its rear end with a laterally extending lug 311 normally engaged above or on a lip 312 provided at the lower end of a lever 313. The lever 313 is pivoted at 314 on the frame and has an arm 315 which normally overlies a fixed stud 316. A dog 317 is pivoted on the lever 313 at 318 and has two arms adapted to engage respectively the pivot 314 and also the pivot member 287 connecting the differential key stop bar 248 to the link 246. As the stop bar 248 approaches the normal latched position of Fig. 14 the pivot 247 swings the dog in a counter-clockwise direction (viewing Fig. 15) away from engagement with the pin 314. A two armed lever 319 is pivoted at 320 on the frame and has its upper arm arranged to engage over a contact lug 321 when the lever 319 is rocked and the parts are released by the depression of a key.

A spring 322 is arranged between a lug 323 on 75

the two armed lever 319 and the dog 317. The lower arm of the lever 319 is arranged for engagement by the plate 292 of the continuous reciprocating lever 289 and, except when a key is depressed, the two arm lever 319 rocks idly back and forth. Upon depression of a key, the differential stop bar 248 moves toward the rear of the machine taking with it the pivot stud 247. This permits the spring 322 to swing the dog 317 into position to arrange the lug 321 in the path of movement of the upper arm of the two armed lever 319. Upon engagement of the plate 292, with the lever 319, and continued movement, the lever 319 and the dog 317 are swung as a unit toward the left (viewing Fig. 15—*a*), moving the lip 312 forwardly and from under the shoulder lug 311 of the hook member 294. This permits the hook member under tension of spring 299 to drop down into engagement with the reciprocating plate 292 and thereafter, at each reciprocation, an adding accumulation of the set-up multiplicand is imparted to the numeral wheels through the arm 277, link 275, arm 273 and shaft 222, as already described. It will be noted that the initial engagement of the hook with the plate 292 is delayed a full reciprocation of the plate, giving the rack segment the small but needed time to assume its controlling position after depression of a multiplier key.

30 The ratchet segment 243 is swung downwardly and toward the front a distance determined by the digital key 231 depressed, being halted in this downward movement by the differentially arranged stop lugs 253 on the bar 248. An arm 324 is mounted upon the rod 98 adjacent the ratchet segment 243, conveniently having a hub 325 embracing the rod and upon which is pivotally mounted the ratchet segment 243. This arm is connected by a link 326 at its lower end to the pivot 274 located at the upper end of the arm 273 which rocks with the arms 223 on the shaft 222.

The arm 324 carries a pawl 327 pivoted at 328 in the lower end of the arm 324 and arranged in position to engage the teeth of the ratchet segment progressively to move it back toward normal position one tooth for each oscillation of the shaft 22. A spring 329 fixed at one end at 331 to the pawl 327 and at the other at 332 to the arm 324 normally pulls the pawl into ratchet teeth engaging position. When the parts are arranged in normal position, the pawl is held out of engagement with the ratchet teeth by a fixed cam 333 fast upon an adjacent frame part, under which the lip of the pawl rides to move it downwardly to an inoperative position. At each stroke or oscillation of the shaft 222, the pawl rides off this cam and into engagement with the presented tooth of the ratchet advancing it one tooth part per oscillation.

65 A back stop pawl 334 pivoted at 335 on an adjacent frame plate is provided to engage and hold the ratchet segment as it is progressively advanced by reciprocation of the pawl 327. A locking detent for locking the back stop pawl 334 out of operative position at the end of a calculation, so that the ratchet segment may freely swing the amount determined by the particular digital key depressed, is provided, and comprises 70 a latch 336 pivoted at 337 on the frame and arranged in position to engage a locking lug 338 formed on the back stop pawl 334.

A spring 339 is arranged to connect the lower end of the back stop pawl 334 and the latching member 336, normally pulling the back stop pawl

334 toward the ratchet segment and the latching member in a counter-clockwise direction (viewing Fig. 16) and into engagement with the actuating pawl 327. The back stop pawl 334 is provided with a finger 341 extending across the path of travel of a pin 342 on the forward edge of the ratchet segment 243. When the ratchet segment has been returned in its tooth-by-tooth movement to normal position, the pin 342 engages the finger 341 and swings the back stop pawl 334 downwardly, arranging the lip 338 in position for engagement beneath the latch 336 so that the back stop pawl 334 is thereafter held down out of operative position until the ratchet segment is again moved for an adding calculation.

The spring 279 at the end of a calculation holds the links 275 and 326 forwardly upon disengagement of the hook 293 with the plate 292, causing the actuating pawl 327 to ride beneath and be held down by the cam 333. It will, therefore, be noted that no pawls engage the ratchet segment when the parts are in normal non-calculating position.

In order that the equalizing key bar 234 may be held down and the depressed key locked against return movement until the end of the desired number of additive calculations, there is provided a lever 343 pivoted at 344 on the equalizer bar and having a hook 345 at its lower end adapted to engage beneath a lock plate 346 fixed on the frame of the machine. A spring 347 normally swings the lever 343 in a clockwise direction (viewing Fig. 15). The upper end of the lever is adapted to engage a stud 348 mounted upon the link 246 which connects the differential key stop bar 248 with the ratchet segment. When the parts are in normal non-calculating position the stud 348 maintains the lever in the position shown in Fig. 13, pressing it in a counter-clockwise direction against the force of the spring 347. Upon depression of a key and a differential rearward movement of the stop bar 248, the stud 348 moves rearwardly and releases the lever 343, permitting it to latch up as the equalizing key bar 234 reaches the bottom of its movement. Once latched with the lock plate 346 on the frame, the lever 343 holds the parts in operating and repeating position until the return movement of the ratchet segment causes the stud 348 to again engage the lever 343 and release the parallel motion device for return movement.

Means are provided also for insuring against continued actuation as the result of failure to release a key 231 once depressed.

It will be remembered that the latch lever 254 is pivoted at 255 on the differential stop bar 248 and, of course, moves toward the front of the machine as this stop bar is returned toward normal position after a key depression. Just before it reaches its normal position, its rear end 262 engages the upper end of latch lever 259 and swings it to the position shown in Fig. 14, this occurring at the end of the last tooth latch segment advance. The lever 259 is thus disconnected from the lip 309, whereupon the spring 301 swings the hook 293, the spring lever 298 and the arm 304 upwardly, as may be observed in Fig. 14, and out of the path of movement of the plate 292 on the oscillating lever 289. Upon release of the key, the equalizer key bar 234 and the other parts of the mechanism return to their normal position ready for the next actuations.

The carriage in which the accumulator mechanisms or units are mounted is, as has been ex-

plained, shiftable across the units of additive actuating mechanism through a lifting and a sliding motion, these motions being accomplished as described in my earlier filed patent already mentioned, to detrain the gears 79 from the ratchet gear mechanisms 82 in the initial movement of the carriage. The carriage is held up as it is shifted and until it is lowered to retrain its accumulator gears 79 with the then presented ratchet gear mechanisms 82. The carriage may be lifted directly by pulling up on finger pieces 364 arranged at each end of the carriage, or by the turning of a knob 365 arranged at the front of the adding machine and upon a shaft 366 extending to the back and carrying a gear 367 in mesh with a toothed bar 368 in the carriage, all as in my earlier patent referred to. It is desirable that, when the carriage is lifted, either directly or through manipulation of the knob 365, all of the keys 64 and 231 be locked against depression and until reentrainment of the gears establishes co-operation between the accumulator units and the additive actuating mechanisms.

Referring to Fig. 17, which is a section taken through the machine and between the column of multiplier keys and the bank of keys 64, it will be noted that a lever 369 pivoted upon the cross-rod 98, extending across the machine, has its upper end 372 formed for engagement with the forward or free edge of the carriage and that upon lifting of the carriage this end 372 will be swung toward the front of the machine. A shaft 373 extends across the machine and has bearing in the side support plates and in the intermediate partitions. This shaft is provided with an arm 374 having a pin 375 at its end which is engaged in a relatively large opening 376 in the lever 369. A spring 377 normally holds the pin 375 toward the front edge of the opening 376. Lifting of the carriage swings the lever 369 toward the front of the machine and similarly swings the arm 374 and rocks the shaft 373. This shaft carries a dog or latch 378 for each column of keys and the lower end of each of these dogs is provided with a locking lip 379 adapted for engagement beneath a lug or projection 381 provided upon the rear end of the associated equalizing key bar 138, 234 so that when the shaft 373 is rocked, as just described, all the orders, both of the additive actuating mechanism and of the multiplier keys, are locked against operation. Each lip or lug 379 is angularly disposed as is also its co-operating shoulder 381 on the companion equalizer bar. The purpose of this construction is to permit of the locking up of orders of the machine even though other orders may be in depressed condition, the lip 379 of each order depressed moving in above the companion lug or projection 381.

A plurality of counter wheels 382, having ratchet teeth 383, are mounted upon a cross-rod or shaft 384 in the carriage and behind sight openings 385 (see Figs. 1, 5 and 6). A lever 386 is pivoted upon the cross-rod 98 in the frame and carries a pawl 388 adapted to progressively advance the counter wheels 382 as the lever is reciprocated. This lever at its lower end is provided with a jaw 389 in which is engaged a stud 391 upon an arm 392 fixed to the shaft 222. As this shaft is rocked in multiplying and in negative calculation in dividing, the lever 386 is oscillated and the counter wheel engaged with it advanced correspondingly. Shifting of the carriage across the actuating mechanism and the multiplier column presents desired counter wheels for actuation by the lever 386, as just de-

scribed, so that at the end of an example the multiplier or dividend is displayed through the sight openings 385 of the carriage.

Means are provided for insuring complete key strokes of the digital keys 64 of the additive actuating mechanism units, as will now be described, reference being had particularly to Figs. 9 to 12, 5, 15 and 17 of the drawings.

A latch 393 is pivoted at 394 on each bar 145 of each parallel motion device of the adding actuating mechanism. A spring 395 normally presses a lip 396 of the latch 393 up into contact with the under surface of its bar 145. A ratchet tooth 397 is provided upon a ratchet member 398 arranged upon the upper end of a lever 399. The lever 399 is pivoted at 401 in a yoke 402 which in turn is pivoted on a cross-rod 403 extending across the several orders of additive actuating mechanisms. A spring 404 is attached at 405 to the lever 399 and to a lip 406 upon a lever 407 pivoted upon a cross-rod 408. Upon depression of one of the keys 64 the bar 145 is moved toward the front of the machine, i. e. toward the left (viewing Fig. 9), and the latch 393 being carried by it moves with it and past the ratchet tooth 397.

If a key be released without fully effective depression, the forward movement of the link or bar 145 will be incomplete and the spring 161 of the parallel motion device (of which it forms a part) tends to return the parts to their original position without accomplishing the calculating operation. In order to advise the operator that an incomplete key stroke has been made and to insure redepression of the particular key in necessary amount, locking mechanisms are provided, which will now be described. As a result of an incomplete movement and through mechanisms to be now described, all of the columns of keys, except that in which the insufficient key stroke has occurred, are locked against operation as a warning or notice to the operator of an insufficient or incomplete key stroke.

A link 409 is pivoted at 411 to the upper end of the lever 399 and is provided at its rear end with a hook 412 normally engaging a stud 413 fixed in the frame and limiting forward movement of the lever under the influence of the spring 404. The link 409 is pivoted at 414 to the upper end of an arm 415 in turn pivoted at its lower end at 416 in the cross-rod in the frame. This link 409 is provided with a laterally bent or extending lug 417 arranged in the path of an upwardly extending arm 418 attached to a shaft 419 extending past the several orders of the machine. This shaft 419 is provided with an arm 421 extending forwardly of the machine and carrying a lip 422 at its free end. This lip is normally arranged behind and holds forwardly the lower end 423 of a companion arm 424 fixed upon a cross-shaft 425. Rocking of the shaft 419, upon insufficient key stroke in any column, lifts the arm 421 and frees the arm 424 so that it may be brought to locking position as will be now described. The shaft 425 is provided adjacent each column of the machine, including the multiplying column, with a leaf 426 extending out over the tail 427 of a locking dog 428 mounted upon a cross-rod in the machine. Springs 429 normally urge these dogs rearwardly into position to engage beneath shoulders 431 on the forward ends of the equalizer key bars 138, 234. The springs 429 pressing upon the leaves 426 move the arm 424 into a counter-clockwise direction when the arm 421 is lifted by the incom-

plete key stroke of a particular column and move also the dogs into locking position into all of the columns except the one in which the insufficient key stroke has occurred. The dog 428 of this column is prevented from engaging beneath its companion shoulder 431 of its equalizer key bar by reason of the circumstance that the latching of the latch 393 has prevented the complete return to normal position of the parallel motion device. This is accomplished through the engagement of the arm 415 with a stop 430 appropriately arranged in the path of the return reciprocation of this arm. It will be noted that since the latch 393 is engaged at this time with the ratchet tooth 397 the link 409 and the arm 415 must move back with the bar 145. Correction of the error by the complete and proper depression of a key permits the parts to return to normal position, whereupon the dog 428 of the column affected moves to locked position and the complete locking of the keyboard is accomplished.

Means are provided for moving the ratchet tooth 397 out of the path of the latch 393 if and when full key stroke is accomplished. An arm 432 is provided upon the yoke 402 to extend across the path of a roller 433 carried upon the link 121. As the parts near the end of the power stroke, the roller 433 engages the arm 432 of yoke 402 and lifts the yoke about its pivot 403 carrying up the lever 399 to raise the ratchet tooth 397 above the lower edge of the bar 145 and out of the way of the latch 393. The yoke 402 has a rearwardly extending arm 434 formed into a bent lip at its end which is adapted to engage beneath a shoulder 435 when the lever 399 is lifted by the roller 433. This lever is held in this upper latched position until near the end of the return stroke when a lug 436 on the bar 145 engages the upper end of the lever 407 to disconnect it from the arm 434, arranging the parts for the next calculating operation. A rearwardly extending lug 410 is provided on the lever 399 for engagement with the rod 403 to limit downward movement under the pull of the spring 404 when the parts are moving from one position to another.

To prevent miscalculation from redepression of a key before the adding operation of the previous stroke is completed, a number of ratchet teeth 437 are arranged on the ratchet member 398 and in position to be engaged and locked by a latch 438 arranged at 439 on the bar 145 as this bar and the key depressed return to normal. It has also been pointed out that the key must be fully depressed or the keyboard locks. After full depression of the key, the lever 399 is lifted and effort to depress the parallel motion device through the key before the adding movement is completed will cause engagement by the latch 438 with one or the other of the teeth 437 since during the return or adding motion of the bar 145 the lever 399 is held in raised position by the lever 407 and is adapted for engagement by the latch 438 if the depression of a key tends or attempts to move the bar 145 in the reverse direction, i. e. upon a new adding actuation.

Referring now to Fig. 17, reference character 451 indicates a key for releasing the column locks set into action by the insufficient depression of a key as just described. The key 451 is provided with a stem 452 which is arranged above a turned-over end 453 of a lever 454 mounted in the column space between the multiplier keys and 75 the additive actuating keys being pivoted upon

a shaft 455 extending across the machine. The lever 454 has a downward projection 456 arranged above a leaf 457 fast in the shaft 425. The position of the parts shown in Fig. 17 is that assumed normally and when keyboard is not locked as a result of insufficient key stroke. It will be remembered that the shaft 425 is swung in a counter-clockwise direction (Fig. 17) by the springs of the latch dogs 428 after an insufficient key stroke. This movement raises the key 451 in position to be depressed by the operator after the correction of error and to release the key locks. Downward movement of the key 451 swings down the leaf 457 and rocks the shaft 425 back to its normal position. This movement rocks the arm 424 toward the front of the machine into reengagement with the arm 421. The latches 428 have been forced down and are held in released position by the arm 421.

After a number has been set up on the keyboard of the additive actuating columns of keys and when the machine is arranged for key-set automatic operation, depression of one of the keys 231 accomplishes a repeated adding operation or a multiplication or a division, depending upon whether positive or negative calculation is being undertaken. This results in the accumulation of the accumulator units co-operatively connected by the position of the carriage with the orders of keys in which keys have been depressed and set. Assuming that the first calculation is of the multiplicand to the amount of the digital value of the unit of the multiplier, the carriage may then be moved one column to the right and the multiplier key depressed to accomplish automatic multiplication to the intended digital value of the 10's order of the multiplier, and so on until the example is completed. Thus with a single order of multiplier keys, the accumulation of the accumulator units is readily obtained. The multiplicand appears in the set-up keys on the board. The multiplier appears on the counter wheels seen through the sight openings 385, and the product appears upon the numeral wheels seen through the sight openings 76 of the carriage.

Zeroizing of the accumulator and resetting of the carriage into a desired starting position after a computation is accomplished by pulling forwardly the combined zeroizing and carriage resetting lever 458. In moving this lever forward, the carriage is lifted and the carrying springs released, as in Patent No. 1,926,826, so that with the carriage so lifted it may be moved to the desired starting point for the next calculation.

Means are provided in the machine for permitting the correction of an error in setting up the keys of a multiplicand or a dividend. A button 265 is arranged in front of each bank or column of keys of the adding actuating mechanism. The button is provided with a stem 266 arranged through the housing 267 in the casing. The lower end of the stem bears upon a ledge 268 upon a rocker bellcrank 269 pivoted upon a cross-rod 214. A stud 461 is arranged upon the upper arm of each rocker bellcrank (there being a rocker bellcrank provided for each additive order of the mechanism), which stud is adapted for engagement with an upwardly extending arm 462 formed integral with the latch 207. Depression of the button 265 of a column in which a key has been set causes unlatching of the latch extension 205 of the bar 145 from the lug 206 of the latch 207 and permits the parts to return to normal unset position.

Means are also provided to prevent engagement of the latch 393 with its companion tooth 397 as the parts move back to position after such a release. It will be remembered that these latches are rendered inactive only after a forward adding movement of the link 121. Thus under key-set action if it is desired to clear a key in any column prior to an adding actuation in that column, the latch 393 must be cleared or the return of the link 145 will set the keylocks of the whole keyboard. This bar has no forward movement prior to a resetting operation. This means will be described in connection with the mechanism which is provided to reset all of the keys after a calculation has been completed.

Referring to Figs. 1 and 17, it will be noted that a key 463 is provided between the board of additive actuating mechanism keys 64 and the column of multiplier keys 231. This key has a stem 464 which rests upon a lip 465 of a three-arm lever 467 pivoted at 468 in the frame. The forward arm 469 of this lever is arranged beneath a stud 471 on an arm 472, keyed to shaft 211. Downward depression of the key 463 rocks the lever 467, lifting the stud 471 and rocking the shaft 211 in a counter-clockwise direction (viewing Figs. 5 and 17). This rocking movement forces the latches 207 down to free all of the units of adding actuating mechanisms. This rocking of the shaft is permitted by the slot 218 and pin 219 connection (Fig. 19), the spring 221 returning the parts to normal operative position after a releasing movement.

The lever 467 has a third arm 473 extending down and forwardly and pivotally connected at 474 with a link 475 extending back and connected by a pin and slot connection 476 with a downwardly extending arm 477 mounted upon a rock shaft 478 which extends across the machine in bearings 479. At each adding order of the machine, an arm 481 is fixed on the shaft and carries a pin 482 arranged beneath a tail 483 forming a part of the associated latch 393, the tail of the latch being directly over the stud when the parts are arranged in key set position. Pressing of the button 463 accordingly through the linkage mechanism described swings the arms 481 up to move the latches 393 to released position as an incident to the release of the latches 207.

The shaft 484 is arranged near the front of the machine and is provided with an arm 485 having a stud 486 arranged to be engaged and swung by the lower end 487 of the rocker bellcrank 269, already described, when this rocker bellcrank is depressed by its companion button 265.

Referring now to Fig. 3, it will be noted that shaft 484 carries a downwardly extending arm 488 connected at 489 to a link 491 pivoted in turn at 492 to an arm 493 fixed upon the shaft 478. This shaft has also an arm 494 extending downwardly and engaged by a spring 495 connected at one end of the arm 494 and at the other end to cross-rod 408. Depression of any one of the buttons 265 through the linkage mechanism just described imparts a like reciprocation to the shaft 478 and a like movement of the arms 481 up into position to release the latches 393 so that the particular adding mechanism in which the latch 207 has been concurrently disengaged may rise back to normal position.

As in my patent earlier mentioned, I provide subtraction mechanism, generally indicated at

497, controlled by a key 438 which, being duplicate of like mechanism in my earlier mentioned pending application, does not require particular description here.

Means are provided for locking the multiplier keys 231 against depression when the machine is arranged for key-responsive operation. It will be remembered that the shaft 201 is rocked with the walking beam lever 185 to convert the machine from a key-responsive to a key-set control and vice versa. Shaft 201 (Figs. 13 and 19) is provided at its righthand end with an arm 200 which is formed into a lug 499 adapted to engage beneath a shoulder lug 501 when the shaft 201 is arranged in or rocked to the position shown in Fig. 13, which is the position it assumes when the machine is arranged for key-responsive action of its ordinal actuating mechanisms. When the parts are in this position, the arm 200 prevents depression of the bar 234 and all of the keys 231 are locked against actuation.

While the invention has been hereinabove described and explained as incorporated in an adding or calculating machine wherein progressive adding actuations are received for all forms of calculation and by progressive advancement accumulators, it will be readily understood that from many standpoints the invention can as readily be incorporated in calculating machines of other types and wherein additive actuation is accomplished other than by mere progressive and successive advancement of the accumulators.

It is thought that this invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a calculating machine having a plurality of denominational orders of actuating mechanism, a power unit for operating said actuating mechanism, and a clutch for each order of said actuating mechanism selectively and individually controlled to deliver power in set increments of action to a said order of actuating mechanism from said power unit; a multiplier control mechanism for automatically controlling the denominational actuating mechanism, including means for repeatedly and positively engaging said clutches with said power unit a predetermined number of times.

2. In a calculating machine having the combination of accumulator mechanism, denominational orders of actuating mechanism for said accumulator mechanism, key devices for digitally controlling said actuating mechanism, denominational power operated devices, and multiplier keys for controlling the number of operations of said denominational orders of actuating mechanism as selectively determined by said key devices; mechanism controlled by said multiplier keys for positively and repeatedly engaging said selected orders of actuating mechanism with said power operated devices, including means adapted to be operated a predetermined number of times as determined by a said multiplier key, and a member in each denominational order operated by said means to engage its related actuating mechanism with the associated power operated device.

3. In a calculating machine the combination

of an accumulator, actuating mechanism for said accumulator, continuously rotating power driving mechanism for said actuating mechanism, connecting devices between said power mechanism and said actuating mechanism for transmitting power from said power driving mechanism to said actuating mechanism, means urging said connecting devices into ineffective position, a keyboard containing keys for controlling the digital actuation of the actuating mechanism, means actuated by any one of said keys and acting to overcome said urging means to cause operation of said actuating mechanism by said power mechanism, means for disabling said overcoming means, and a second keyboard containing keys rendered effective by said disabling means for controlling mechanism acting to overcome said urging means to cause actuation of said actuating mechanism by said power mechanism.

4. In a calculating machine, the combination of an accumulator, actuating mechanism for said accumulator optionally operable for key-responsive actuation and key-set actuation, means for determining the character of actuation, power driving mechanism for said actuating mechanism, connecting devices between said power mechanism and said actuating mechanism for transmitting power from said power driving mechanism to said actuating mechanism, means urging said connecting devices into ineffective position, keys for controlling the digital actuation of the actuating mechanism, means actuated by any one of said keys when said actuating mechanism is arranged for key-responsive actuation and acting to overcome said urging means to cause operation of said actuating mechanism by said power mechanism; and means for rendering said last named means ineffective when said actuating mechanism is arranged for key-set actuation.

5. In a calculating machine, the combination of an accumulator, actuating mechanism for said accumulator optionally operable for key-responsive actuation or a key-set actuation, means for determining the character of actuation, power driving mechanism for said actuating mechanism, a connecting device between said power mechanism and said actuating mechanism for transmitting power from the power driving mechanism to the actuating mechanism, means for releasably holding said connecting device in an ineffective position, keys for controlling the digital actuation of the actuating mechanism, means actuated by any one of said keys to overcome said holding means, means operable in response to depression of such key when said actuating mechanism is arranged for key-responsive actuation to move the connecting device to effective position to cause operation of said actuating mechanism by the power mechanism; and means for rendering the key-responsive means ineffective when the actuation mechanism is arranged for key-set operation.

6. In a calculating machine, the combination of an accumulator, actuating mechanism for said accumulator optionally operable for key-responsive actuation or key-set actuation, means for determining the character of actuation, power driving mechanism for said actuating mechanism, connecting devices between said power mechanism and said actuating mechanism for transmitting power from the power driving mechanism to the actuating mechanism, means for releasably holding said connecting devices in an ineffective position, adding keys for controlling

the digital actuation of the actuating mechanism, means actuated by any one of said keys to overcome said holding means, means operable in response to the depression of such key when said actuating mechanism is arranged for key-responsive actuation to cause operation of said actuating mechanism by the power mechanism; multiplier mechanism having multiplier keys for controlling the number of operations of the actuating mechanism when the machine is arranged for key-set operation; and means for rendering said key-responsive means ineffective when the machine is arranged for key-set operation and for rendering the multiplier keys inoperable when the machine is arranged for key-responsive actuation.

7. In a calculating machine having an accumulator mechanism and actuating mechanism therefor, power mechanism, a normally disengaged connector between said power mechanism and the actuating mechanism; keys for gauging the digital actuation of said actuating mechanism, means for releasably holding said connector in disengaged position, means actuated by any one of said keys to release said holding means, means operable in response to depression of such key to cause the connector to engage with the power mechanism to effect operation of the actuating mechanism to operate the accumulator mechanism, and other means acting to cause said connector to engage the power mechanism and cause repeated actuation of said actuating mechanism.

8. In a calculating machine having an accumulator and actuating mechanism therefor; power mechanism comprising a denominational rotor for operating said actuating mechanism; a connector for connecting said actuating mechanism with said rotor; digital keys for controlling the digital degree of actuation of the actuating mechanism; mechanism operated in response to depression of any of said keys to move the connector into engagement with the rotor to impart a power action to the actuating mechanism; multiplier mechanism operated by said power mechanism and acting upon said connector to cause repeated engagement thereof with said rotor; and multiplier keys for controlling the multiplier

mechanism to control the number of actions upon the connector.

9. In a calculating machine having a multiplicity of denominational orders of the accumulator mechanism including registering wheels and their associated carrying mechanism mounted in a shiftable carriage: a multiplicity of independent orders of power operated actuating mechanism to cooperate with the accumulator orders including normally disengaged connectors between the power mechanism and the actuating mechanism, keys for gauging the digital actuation of said actuating mechanism, means for releasably holding said connectors in disengaged position, means actuated by any one of said keys to release said holding means, means operable in response to depression of such keys to cause the connectors to engage with the power mechanisms to effect operation of the actuating mechanism to operate any accumulator registering wheel which is held in alignment with said actuating mechanism by the carriage, and other means acting to cause said connectors to engage with the various orders of power mechanism to cause repeated actuation of said actuating mechanism.

10. In a calculating machine: an accumulator mechanism including registering wheels and their associated mechanisms mounted in a shiftable carriage in rear of the keyboard of the machine; independent denominational orders of actuating mechanism operable with the selected superposed mechanisms of the accumulator depending upon the position of said shiftable carriage; power mechanism having denominational rotors for operating said actuating mechanisms; connectors for connecting said orders of actuating mechanism with said rotors; digital keys for controlling the digital degree of actuation of the various orders of the actuating mechanisms; mechanism operated in response to depression of any of said keys to move the connectors into engagement with the rotors to impart a power action to the actuating mechanisms; multiplier mechanism operated by said power mechanism and acting upon said connectors to cause repeated engagement thereof with said rotor; and multiplier keys for controlling the multiplier mechanism to control the number of actions upon the connectors.

CERTIFICATE OF CORRECTION

Patent No. 2,241,102.

May 6, 1941.

JOSEPH A. V. TURCK.

It is hereby certified that error appears in the printed specification of the above numbered patent requiring correction as follows: Page 2, second column, line 51, for the word "rock" read --rack--; page 6, second column, line 48, for "shaft 22" read --shaft 222--; page 8, first column, line 74, for "into" read --in--; page 10, second column, line 70, claim 6, for "connecting devices" read --a connecting device--; line 74, same claim, for "devices" read --device--; page 11, first column, line 6, same claim 6, before "cause" insert --move the connecting device to effective position to--; and that the said Letters Patent should be read with this correction therein that the same may conform to the record of the case in the Patent Office.

Signed and sealed this 17th day of June, A. D. 1941.
